UNITED STATES PATENT OFFICE.

HENRY L. BRUGGEMANN AND CHARLES G. ORTH, OF CLEVELAND, OHIO.

STRIKING-CLOCK.

SPECIFICATION forming part of Letters Patent No. 337,736, dated March 9, 1886.

Application filed August 27, 1885. Serial No. 175,500. (No model.)

To all whom it may concern:

Be it known that we, HENRY L. BRUGGEMANN and CHARLES G. ORTH, both of Cleveland, in the county of Cuyahoga and State of Ohio, 5 have invented certain new and useful Improvements in Striking-Clocks, of which the following is a specification.

This invention has for its object to provide a means for repeating the striking of the hour 10 at any time between hours, and also for changing the striking from one bell to another every half hour. We attain these objects by the mechanism illustrated in the accompanying drawings, in which—

15 Figure 1 is a front elevation of a clock mechanism having our improvements attached. Fig. 2 is a detached view of the repeating mechanism, and Fig. 3 is a detached view of the hammer-changing mechanism. These views 20 are drawn full size.

A represents the supporting frame.

B is the count-wheel connected with and operated by the striking-train. This wheel is provided with stop-pins b, projecting from the 25 side of the wheel, and are in number equal to the twelve hours. These stop-pins strike against the end of a spring, C, attached to the frame A, as will be hereinafter shown in description of operation.

30 D is a lift-lever, which serves to stop the train by its hook dropping into the deep notches, and is that of the construction now in common use. To accompany this lift-lever is a second lever, E, pivoted to the frame A at 35 e, and is located beneath said lift-lever D.

F is a bent lever attached to a shaft, f, journaled in the frame A, its lower end reaching under the said lever E, its upper end standing above the frame, and is provided with a cord, 40 f', passed out through the clock-case, by which said lever may be pulled, when desired, for the purpose of the repeated striking, as will be hereinafter shown.

The count-wheel has several pins, p, attached 45 midway between its center and periphery and located on its opposite side to those of b.

To the lower part of frame A is attached a spring, G, the upper end of which bears against said pins, the purpose of which is to throw the 50 count-wheel backward when the lift-lever is raised, said backward movement being limited by the aforesaid stop-pin b.

The operation of this is as follows: By the position of the count-wheel, as shown in Figs. 1 and 2, the clock struck twelve last. Now, 55 by pulling on cord f' lever F is drawn upon. This raises levers E and D, thus releasing the count-wheel. Then the spring G throws said count-wheel backward until stop-pin b' strikes the spring C. At the same time levers D and 60 E are lifted, a lever, H, on shaft h is also lifted. This carries upward a lever, L, on said shaft h, which catches a pin, l, on wheel M of the striking-train, thereby arresting the forward movement of the train and giving time 65 for the count-wheel to move back. Now, by letting go of the cord, the levers D and E drop again to their places and the hour before struck is repeated. This repetition may be struck as often as desired between hours, the 70 change from one hour to the next being made in the usual manner. This repeated striking is limited to within five or six minutes of the succeeding hour to prevent the change taking place before the minute-pointer has reached 75 the full hour. This is caused by means of a lever, I, attached to the same shaft that the lever F is, engaging with a hook, J, on minute-hand shaft Y, which prevents the lifting of levers D and E until said hook has passed over 80 the meridian-point. Then the clock will strike the succeeding hour, and will repeat that hour until the minute-pointer again passes around to within the five minutes before the completion of the hour.

85 The hammer-changing mechanism, the second part of our improvement, is described as follows: On shaft S, to which the hammer-lever is usually attached, we put a sleeve, S', and attach the hammer-lever T to it. This 90 sleeve is made to slide longitudinally on the shaft every half hour for changing the stroke of the hammer from one bell to the other. On the said shaft is also placed a spiral spring, S'', the tension of which is to force the sleeve back 95 upon the shaft. Said sleeve is moved by means of a lever, V, pivoted at its middle part to a stud, U, on the back frame, the lower end of said lever bearing against a lip on the end of sleeve S'.

100 The lever V is actuated by a half-disk, W, on the back end of minute-hand shaft Y. During one-half of the revolution of said shaft Y the said disk pushes and holds outward the

upper end of said lever V, the lower end forcing the sleeve S' forward on its shaft, thereby carrying the hammer forward, so as to strike the wire gong. During the other half-revolution the lever V is released from said half-disk. This allows the sleeve to slide back on the shaft, thus carrying the hammer back, so that it will strike the second gong or bell. The object of this is to provide a different sound 10 for the latter half hour.

Having described our invention, we claim as follows:

1. In striking-clocks, the combination, with the count-wheel provided with the two sets of 15 pins *b* and *p*, of the spring *G* and stop-spring *C*, the levers *D* and *E* lifted by lever *F*, which releases the hook of lever *D* from the count-wheel, also lifting the lever *H*, having the lever *L*, which engages with pin *l* on wheel *M*, for ar- 20 resting the starting of the striking-train while the spring throws the said count-wheel backward, said lever *F* also carries a lever, *I*, forward to engage with a hook, *J*, on minute-shaft *Y* at a given point in its revolution, the

operations of said mechanism enabling the 25 striking mechanism to repeat the hour last, substantially as described.

2. In a striking-clock, the combination, with the repeating mechanism thereof, of the lever *T*, fixed to the sleeve *S'*, and having the upward extension engaging with and operated by the striking-train, said sleeve *S'* being loosely placed on the hammer-shaft *S*, and made to slide thereon by the spring *S²* in one direction, the other end of said sleeve having 35 an extension bearing against the lever *V*, pivoted at its middle to the frame *A*, its upper end being actuated by the half-disk *W* on minute-hand shaft *Y*, by means of which the hammer-lever is shifted forward and back 40 every half hour to cause a part of the repeated striking to be performed on the two bells, as described.

HENRY L. BRUGGEMANN.
